Patented Nov. 12, 1929

1,735,402

UNITED STATES PATENT OFFICE

WILLIAM L. KNIESEL, OF SAN DIEGO, CALIFORNIA

BOILER COMPOUND

No Drawing.

Application filed November 14, 1927. Serial No. 233,317.

My invention relates to a compound for boilers and the objects of my invention are: first, to provide a compound to be used in boilers that will remove and dissolve the scale; second, to provide a compound of this class that will prevent the fluid in the boiler from foaming; third, to provide a compound of this class which is harmless when used around and in connection with edible products; fourth, to provide a new and novel compound for boilers, and fifth, to provide a compound of this class which is simple to compound, easy to apply and efficient in its action.

With these and other objects in view as will appear hereinafter, my invention consists of a novel compound as will be herein-after described in detail and particularly set forth in the appended claim.

My invention consists in its preferred form of the following ingredients, combined in the proportions stated, to wit:

	Pounds
Silicate of soda-----	1200
Caustic soda-----	120
Extract of hemlock, containing tannic acid-----	10
Gum catechu-----	10
Sorghum molasses-----	12

However, I have found by experimentation that other tannic acids such as extract of oak or walnut will perform the function to a certain degree.

These ingredients are placed in a vessel heated to a boiling point and thoroughly agitated, forming the compound, after which they are placed in a receptacle ready for use.

Having thus described my invention, what I claim as new and desire to secure by Letters Patent, is:

A boiler compound comprising silicate of soda, twelve hundred pounds, caustic soda, one hundred twenty pounds, extract of hemlock containing tannic acid, ten pounds, gum

catechu, ten pounds, and sorghum molasses, twelve pounds.

In testimony whereof, I have hereunto set my hand at San Diego, this 2nd day of November, 1927.

WILLIAM L. KNIESEL.
